UNITED STATES PATENT OFFICE.

JÖRGEN JACOBSEN, OF ELSINORE, DENMARK.

APPARATUS FOR LIGHTING AND EXTINGUISHING GAS-FLAMES.

No. 895,642.

Specification of Letters Patent.

Patented Aug. 11, 1908.

Application filed October 4, 1906. Serial No. 337,364.

To all whom it may concern:

Be it known that I, JÖRGEN JACOBSEN, captain, a citizen of the Kingdom of Denmark, residing at Bjergegade 18, Elsinore, Denmark, have invented a new and useful Improvement in Apparatuses for Lighting and Extinguishing Gas-Flames; and I do hereby declare the following to be a full, clear, and exact description of the same.

This invention relates to improvements in apparatus for lighting and extinguishing gas at a burner, by means of the pressure of gas in the conducting system, which can be repeatedly increased and diminished to control the selection of the lanterns to be ignited and extinguished, thus permitting the gas-works to fully manage all of the lanterns, to light all of them or one or several groups of them, and also to extinguish certain groups of lanterns, while other ones remain lighted, and finally to extinguish the latter ones.

In the drawing, showing a form of the apparatus, Figure 1 represents a vertical longitudinal section through the apparatus; Fig. 2 shows a top view of the apparatus without the cover and Fig. 3 shows a vertical cross section of the apparatus on the line A—B of Fig. 1.

To the casing 1, of the apparatus, is screwed a bottom 3 with a rectangular ring-like continuous canal for receiving quicksilver. This quicksilver is intended to sustain or float an inverted reservoir 4, constituting a float which is in connection with a pipe 5 which is in communication with an opening through the top of the float 4. At its upper end, pipe 5 has a connection with pipe 6 which is turnable in a bearing 23, in which there is provided a hollow box 7. Thus the float may rise and fall without interrupting the flow of gas through the pipe 5. Upon the float 4 is arranged a chamber 13, in which small-shot and the like can be filled for the regulation of the load of said float.

The pipe 6 is discharged by a hole 26 (Fig. 2) into a passage 8, which communicates with a pipe 9, on which a gas-burner is placed. In the bottom, 3, of the apparatus is provided an inlet-opening 2, for the gas.

On the pipe 5 (Fig. 2) is arranged an upwardly and inwardly-disposed angle-arm, 14, bearing a projection 15. In the casing of the apparatus, is a wheel 11 revolving around a pivotal screw 16. Said wheel has ratchet teeth at its periphery and, at the side, bears a flange, 17, with angular teeth, against

which the projection, 15, either strikes or with which same gears according to the position of the float 4. Said float, or (more exactly the reservoir 13) carries a fitting, 18, 60 having a pawl, 10, which turns about a screw 27, and which—when the float is lifted will engage the ratchet teeth of the wheel 11, and partially rotate the latter whereas this will remain stationary when the float is 65 lowered. To hold the wheel 11 from turning back, there is a pawl 12, on a peg, 20, around a screw 21. On the float 4 is placed another open reservoir, 38, for receiving quicksilver; through this reservoir passes a 70 narrow pipe 37, (Fig. 3) in line with the inlet-opening 2. Above the reservoir 38, is arranged another fixed reservoir, 28, which has an open bottom, and into which the pipe 37, is arranged to discharge. A passage 29, 75 leads from reservoir 28 to a vertical passage or pipe 24, at the back of the casing 1, and which is connected at its bottom, by a passage, 30, with the inlet-opening 2, (and the size of which passage is regulated by a screw 80 25) and its upper end with a lighting tube. The communication between the pipe, 29, and the pipe, 24, is (Fig. 3) regulated by a screw 31. In the bottom 3 and the reservoir 38 are (at the back of each) provided discharging- 85 holes, 32, and 33, for quicksilver, and these holes are closed with shutters or the like.

In the upper wall of the casing 1 funnel-shaped openings 36 are arranged, through which the quicksilver is filled in. 90

In order to adjust the cog-wheel 17, for the desired purpose, this communicates with a hand 34 which is arranged on the back of the apparatus and adjusted by means of a spring-pin 35. 95

When the apparatus is to be operated, the quicksilver is filled in until this is discharged through the opening 32, and the lighting flame is lighted. If the pressure of the supplied gas is increased at the supply station, 100 the float 4 and the pipe 5 will be lifted, whereby the wheel 11 is moved. If it is not intended by this pressure, to light the lantern, the cog-wheel must beforehand be constructed or disposed in such way that the projection 105 15 falls against one of the side teeth of the cog-wheel, and the lantern will then only be lighted after the pressure has been diminished and then again is increased, as the projection, 15, then will fall between two teeth on the 110 cog-wheel. If it is intended to light the lantern by the first increase of the pressure,

the cog-wheel must be constructed in such way that the projection 15 can at once pass through. For a lantern which is to be extinguished by the first diminution of pressure, 5 the interval between the corresponding teeth on the cog-wheel must be so large that the projection 15 on the way back again can pass between the side teeth of the wheel. If, however, the lantern is to remain lighted 10 despite the diminution of pressure, the cog-wheel must, by its continued rotation during the successive lifting of the reservoir at last show a tooth below the projecting tooth 15, so that the latter, when the reservoir tends 15 to be lowered, will strike against the cog-wheel and thus stop the lowering of the reservoir, whereby the introduction of gas is continued without any hindrance. When the necessary higher pressure again is produced 20 the wheel will rotate, and by ensuing diminution of the pressure the reservoir can again fall to have the pipe 5 immerse in the quicksilver, and the inlet of gas is interrupted. When the float 4 is lowered the gas will 25 pass through the pipes 27, 29 and 24 to the lighting-flame. If the large flame is to be lighted, the float 4 is lifted and with it the reservoir 38; the pipe 29 will then be immersed 30 in the quicksilver in the reservoir 38, and thereby interrupt the inlet of gas to the lighting flame. However, in order to have a small lighting flame burning, while the large flame is lighted, the aforesaid small narrow communication, 30, is provided between 35 the inlet-opening 2 and the pipe 24, thus automatically assuring that the lighting-flame shall be always burning.

What I claim and desire to secure by Letters Patent of the United States is:

40 1. In an apparatus for igniting and extinguishing gas at a burner, a casing provided with a burner and having means for supplying gas to said burner and comprising a container for quicksilver, a movable float dip-

ping into said container for immersion in the 45 quicksilver when in said container, a wheel provided with teeth, a projection carried by the float, and a pawl movable by the float and intermittently operating the wheel to cause the teeth on the wheel to intercept the 50 projection aforesaid or to permit it to pass between such teeth.

2. In an apparatus for igniting and extinguishing gas at a burner, a casing provided with a burner and having means for supplying gas to said burner and comprising a container for quicksilver, a movable float dipping into said container for immersion in the quicksilver when in said container, a ratchet wheel having peripheral teeth and 60 equidistant teeth upon one of its sides, a pawl movable by the float and engaging with the peripheral teeth of the wheel for intermittently moving the latter, and a projection carried by the float and movable into 65 engagement with or between the side teeth of said wheel.

3. In an apparatus for igniting and extinguishing gas at a burner, a casing provided with a burner and having means for supplying gas to said burner and comprising a gas inlet to the lighting flame, a container for quicksilver, a movable float dipping into said container for immersion in the quicksilver when in said container and a reservoir carried by said float and containing a body of quicksilver to close the aforesaid gas inlet, in combination with a wheel having teeth and with a projection carried by the float and movable into engagement with or be- 75 tween the teeth of said wheel.

In testimony whereof, I have signed my name to this specification in the presence of two subscribing witnesses.

JÖRGEN JACOBSEN.
